UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,184,228

Specification of Letters Patent.

Patented May 2, 1916.

Application filed May 9, 1912. Serial No. 696,103.

To all whom it may concern:

Be it known that I, HAAKON A. MARTIN, a citizen of the United States, residing at Dayton, in the county of Montgomery and

5 State of Ohio, have invented certain new and useful Improvements in Cash-Registers, of which I declare the following to be a full, clear, and exact description.

This invention relates to sales recording 10 and registering apparatus and among its objects are to provide printing mechanism constructed to print triplicate records of sales on inserted sales slips, and totalizing mechanism for separately totalizing the 15 amounts of such sales according to departments or classes of transactions, and simultaneously to totalize in another totalizer the aggregate of the individual totals.

Another object of the invention, for the 20 purpose of selecting a desired totalizer for operation, is to provide means operated through direct connections with depressible keys for adjusting a set of multiple totalizers to different extents with respect to 25 actuating devices therefor.

Another object of the invention is to provide a novel and useful alining device for a multiple totalizer carrying frame, which device serves to aline the frame so that the 30 totalizer which is in the plane of certain actuating racks will be accurately engaged therewith upon a rocking movement of the frame, and which alining device remains in engagement with the frame during its rocking 35 movement.

Another object of the invention is to provide a differentially adjustable receptacle having a plurality of compartments for receiving stubs in classified order cut from 40 sales slips printed by the machine.

Another object of the invention is to provide improvements in design or cipher eliminating mechanism for the printing mechanism and having the well known function of 45 preventing the printing of ciphers to the left of the highest numeral of any record, but which mechanism is particularly adapted for the elimination of ciphers in that class of printing devices wherein the type 50 carriers are differentially set directly from the position to which they were set on a preceding operation to a desired new position without first being returned to a home or zero position.

55 A further object of the invention is to

provide an improved mechanism for controlling total and subtotal printing in the multiple totalizer machine.

With these and incidental objects in view, the invention consists in certain novel features of construction and combinations of parts, the essential elements of which are set forth in the appended claims, and a preferred form of embodiment of which is hereinafter described with reference to the drawings which accompany and form part of the specification.

Of said drawings; Figure 1 is a right side elevation with the casing omitted. Fig. 2 is a transverse vertical section taken at the 70 side of a bank of value keys. Fig. 3 is a detail in transverse vertical section of the totalizers and one of their operating segments. Fig. 4 is a plan view of the department totalizers. Fig. 5 is a transverse vertical section taken at the side of the bank of department keys. Fig. 6 is a detail of a plate controlled by the bank of department keys for in turn controlling machine releasing mechanism. Fig. 7 is a detail of a 75 differentially movable plate under the control of a bank of department keys and for positioning the department totalizers for operation. Fig. 8 is a detail of the department totalizer selecting mechanism. Fig. 9 80 is a transverse vertical section taken at the side of a lever for controlling the machine in total and subtotal printing operations. Fig. 10 is an enlarged detail in left side elevation of a totalizer engaging mechanism 85 showing particularly the pitman which is employed in adding operations. Fig. 11 is a rear view of the mechanism shown in Fig. 10. Fig. 12 is a detail in left side elevation of the totalizer engaging mechanism showing particularly the pitman which is 90 employed to engage the totalizers for total printing. Fig. 13 is a detail in left side elevation of the totalizer engaging mechanism showing particularly the pitman which is 95 employed to engage the totalizers for subtotal printing operations. Fig. 14 is a transverse vertical section taken through the printing mechanism. Fig. 15 is a detail in left side elevation of the slip feeding mechanism. Fig. 16 is a detail in left side elevation of the platen and its operating cam. Fig. 17 is a detail in right side elevation of the type setting mechanism and cipher eliminating devices associated therewith. 100 105 110

Fig. 17^a is a detail in right side elevation of a type carrier and its setting segment as it would appear when the cipher on the type wheel is at the printing line. Fig. 18 is a 5 front view of the type setting segments and the cipher eliminating devices. Fig. 19 is a detail in right side elevation of the dating device. Fig. 20 is a detail in right side elevation of an operator's key employed for 10 unlocking the machine and carrying type characters for identifying the operator. Fig. 21 is a perspective view as it would appear from the rear of the machine, of mechanism for releasing the machine and associated devices.

The invention relates to improvements in machines of that general type known as department store registers. Its functions, aside from segregating in classes the 20 amounts accumulated, are in most essentials similar to the functions of the cash registers shown in the patents to Thomas Carroll No. 980,201, granted January 3rd, 1911, and No. 934,994, granted September 28th, 1909.

25 The keyboard and differential mechanism and the main totalizer employed in the present invention are in design similar to such devices as appear in the copending application for patent of Kettering and 30 Chryst, cash register, No. 451,446, filed September 2nd, 1908. Also the arrangement of department totalizers is as shown in a copending application of Kettering and Chryst, registering mechanism, No. 376,830, filed June 1st, 1907.

35 As noted in the above objects, the present invention relates more particularly to multiple totalizer positioning mechanism and to a differentially adjustable sales slip stub receptacle by which the stubs of sales slips printed on are classified in compartments of the receptacle.

40 Incidentally the invention relates to improvements in construction which facilitate the assembling and dismantling of the machine.

The principal mechanical devices employed in the present invention are a driving mechanism, a differential mechanism, 45 totalizing devices and slip printing mechanism which are set by said differential mechanism, and a keyboard comprising value keys, department keys and a manually adjustable lever. The value keys control the differential mechanism for operating the totalizing devices and setting type carriers; the department keys control part of the differential mechanism for the selection for operation of department totalizers; 50 the total printing and reset lever has connections for controlling the differential mechanism to accomplish these functions.

The printing mechanism is particularly adapted for printing in triplicate on inserted sales slips.

Driving mechanism.—To impart power to the various mechanisms of the machine the main drive shaft 1 (Fig. 1) is provided with a gear 2 meshing with gears 3 and 4. The gear 3 meshes with a pinion 5 journaled on a stub shaft 6 and rigid with a crank 7. The gear 4 is fast to a driving shaft 8 to which is fastened a shouldered stop disk 9 normally engaged by a pawl 10 pivoted on a rod 11, and which may be 70 rocked to release the driving mechanism through connections operated by the depression of a department key, as explained farther on. Thus on the depression of a department key the drive shafts 1 and 8 may 75 be rotated by operation of crank 7, two revolutions of which are required to effect the necessary single rotation of the drive shafts on each operation of the machine.

Keyboard.—The keyboard comprises a 85 plurality of denominational banks of value keys 33 (Fig. 2) as required by the predetermined capacity of the machine, a single bank of department keys 21 (Fig. 5), and a manually adjustable lever 131 (Fig. 9c) for controlling totalizing and subtotalizing operations.

The value keys 33, as shown in Fig. 2, control the differential mechanism in its movement and have connections for releasing for operation such elements of the differential mechanism as are required. These keys are depressible against the action of springs surrounding their shanks and have inclined edges 258 which, on their downward movement, engage pins 257 on key detent plates 256 hung from pivot pins 36 by arms 313 and 314. The detent plates 256 carry pins 3561 for engaging shoulders on bell crank zero stops 37 for differential segments 39. The zero stops 37 have lugs 371 normally in the path of shoulders 38 of segments 39. When a value key is depressed its inclined edge 258 engages a pin 257 thus rocking the plate 256 downwardly and causing its pin 3561 to engage the forwardly extending shoulder on the zero stop 37 rocking the stop out of the path of a corresponding segment 39. In this manner the segment is made free to operate upon operation of the driving mechanism.

To lock depressed value keys in their inner positions detent plates 32 are provided on the opposite side of the keys from plate 256, which are also hung from pivot pins 36 by a pair of arms similar to arms 313 and 314 in the manner of plates 256. The detents 32 are provided with pins 34 opposite notches 35 in the keys and each arm 313 to which the lower ends of the detents 32 are pivoted, is forked at its rear end to engage a rod 312 carried by arms 311 fast to a rod 31. By a rocking movement of rod 31 the rod 312 is lifted thereby through arms 313 forcing the detents 32 upward and 120 125 130

causing pins 34 to enter the notches 35 of keys which are not depressed, and notches 258 of depressed keys, thereby preventing manipulation of these keys. The rocking 5 of rod 31 takes place on the depression of a department key.

The department keys 21, shown in Fig. 5, have connections for releasing the machine by rocking pawl 10 (Fig. 1) and for locking 10 the value keys against manipulation by rocking rod 31 (Fig. 2), and for selectively positioning the department totalizer frame 110 (Fig. 4).

The department keys 21 (Fig. 5) are depressible against the action of springs 186 15 extended between pins on the keys and pins on the key frames, and each key is provided with a pin 22 for coöperating with slots 20 in plates 19 hung from pins 2300 on the key 20 frame by arms 23. At its upper end the plate 19 is provided with a notch 25 in which may enter a laterally extending lug 17 on an 25 arm 16 fast to a frame 29 loose on a shaft 14 (Fig. 2). Also rigid with frame 29 is an arm 13 (Fig. 1). Pivoted to arm 13 is a 30 link 12 connecting it to the stop pawl 10 coacting with shouldered disk 9 fast to drive shaft 8. When a department key 20 is depressed its pin 22 through engaging the inclined edge of one of slots 20 in plate 19 forces the plate upward, thus causing its edge 18 to pass away from lug 17 on arm 16, and its notch 25 to come opposite the lug. Arm 16 then rocks upwardly, its lug 17 entering the notch 25 and thereby locking the 35 depressed key in its depressed position as plate 19 cannot then return to normal position. The arm 16 is caused to thus rock by a spring 15 (Fig. 1) extended between a pin 40 on link 12 and a pin on the side frame of the machine. This spring urges the link forwardly, thus, through arm 13, rocking frame 29 (Fig. 2) in a clockwise direction, and as this frame is rigid with arm 16 the latter is 45 rocked in a clockwise direction. The forward movement of link 12 (Fig. 1) rocks stop pawl 10 around its pivot 11 so that the pawl is disengaged from disk 9. In this manner the driving mechanism of the machine is released for operation.

The rocking movement of arm 16 (Fig. 5) as above described, is employed to rock rod 31 for the purpose of locking the value keys from manipulation. For this purpose 55 a link 30 pivoted to the arm 16 (Fig. 5) connects said arm with a rearward extension of one of the arms 311 fast to rod 31, the function of which was previously described. The rocking movement of arm 16, by forcing the link 30 downwardly, effects the required rocking of shaft 31 to lock the value 60 keys.

In order that the department keys may differentially position the department totalizer carrying frame 110 (Fig. 4), the pins 65

22 on the department keys (Fig. 5) also co-operate with a plate 161 best shown in Fig. 7 and having an inclined edge 165 and two inclined slots 166 and 167. The pitch of the inclines is progressive. The plate 161 70 is supported by arms 162 and 163 hung from pivot pins 164 on the key frame. The lower arm 163 has pivoted thereto a link 168 (Figs. 5, 7 and 8) connecting the arm with a segment gear 170 pivoted to a tie bar 171 75 connecting the machine frames. The segment gear 170 has teeth meshing with teeth 172 on a rack 173 secured to the forwardly extending arm 174 of the totalizer frame 110 (Fig. 4). 80

The uppermost department key (Fig. 5) has its pin 22 in such position as not to engage plate 161 when the key is depressed. The second key from the top, by its pin 22 engaging slot 167 when depressed, causes 85 plate 161 to be moved upward slightly. The third key from the top would cause the plate to move upward two units, while the lowest key, by engaging incline 165, forces the plate upward three units. In this manner a differential movement may be communicated to link 168 and through this link cause segment gear 170 to be rocked differentially and thereby, through the rack 173, differentially position the totalizer frame 110 along guide 95 rails 157. However, if the uppermost department key 21 is depressed, as it has no effect on plate 161, the totalizer carrying frame 110 will be permitted to remain in its 100 normal position.

For the purpose of releasing depressed keys at the end of an operation of the machine shaft 1 (Fig. 2) has fast thereon a cam 26 coöperating with a roller 27 on a pitman 28 which is pivoted at its upper end 105 to frame 29 and at its lower end is forked over shaft 1 to be guided thereby. When pitman 28 is lifted by cam 26 frame 29 rocks in a counter-clockwise direction withdrawing flange 17 of pawl 16 (Fig. 5) from notch 11 25 in the department key detent 19 and also permitting link 30 to return to normal position under spring action and thereby, through rod 31 (Fig. 2) and arms 311 carried thereby and the rod 312, forces the key 11 32 locking detents 32 for the value keys downward so that their pins 34 are carried out of the notches in the keys and thus permit the keys to return to their outer position.

To insure the release of the value keys on 12 the downward movement of detents 32, it is also necessary to move the key detents 256 downwardly so that their pins 257 are disengaged from depressed keys. For this purpose frame 185 is loosely pivoted on shaft 14 12 in position to engage the upper ends of the detents 256. Springs 184 are interposed between frame 185 and frame 29. From this construction it follows that when frame 29 13 is rocked in a counter-clockwise direction the 13

4

springs 184 will communicate its movement to detents 256 and thereby cause these detents to carry their pins 257 out of engagement with depressed keys.

- 5 Simultaneously with the release of the keys the stop pawl 10 (Fig. 1) is returned into position to be engaged by disk 9 and thereby stop the driving mechanism of the machine at the proper point in condition to 10 begin another operation. The arm 13 being rigid with frame 29 the return rocking movement of the frame causes link 12 to move to the right and thereby permit pawl 10 to move to stopping position under 15 the action of its spring.

The keyboard is also provided with a lever 131 (Fig. 9) for controlling total and subtotal printing operations. The lever 131 has five different positions, the central 20 one in which it is shown in Fig. 9, being its normal position in which position it permits the machine to operate in a normal manner for accomplishing addition. If the lever is shifted one step above this position 25 it will control the machine for printing a total from the department totalizers, and if it is shifted one step below its central position it will control the machine for printing a total from the main totalizer. If the lever is shifted to its uppermost position 30 then on the operation of the machine a subtotal will be printed from one of the department totalizers, whereas if the lever is shifted to its lowest position a subtotal will 35 be printed from the main totalizer. Another function of this lever is to prevent depression of value keys when the lever is out of its normal position so that the keys may not interfere with total and subtotal printing operations. The lever 131 is pivoted on 40 a rod 61 fixed in the machine frames and is rigid with an arm 247 the surface 248 of which is formed to co-act with a roller 249 on a pitman 250 forked to straddle rod 61 45 to be guided thereby at its lower end and pivoted at its upper end to a short arm 251 fixed to shaft 14. This shaft as shown in Fig. 2 has arms 253 carrying a rod 254 which passes below all of the zero plungers 50 37 for all of the banks of value keys and is thereby adapted to lift the zero plungers out of the path of movement of shoulders 38 on segments 39 when shaft 14 is rocked by the action of cam arm 247 fast to the lever 131. 55 The rod 254 also passes in front of extensions 255 of key detents 256. In this manner the zero plungers are withdrawn from stopping position of the differential mechanism so that it may operate on total printing operations and at the same time the value keys are locked in their outer positions as detent 256 cannot be moved downwardly. The lever 131 has a second means 60 for rocking shaft 14 for the purpose of preventing the depression of value keys when 65

the lever is being moved from one position to another or is in some position intermediate of its five intended positions. These five positions are determined by notches 244 in a fixed plate 245. A pawl or thumb grip 70 243 pivoted to lever 131 has a shoulder 242 for entering the notches 244. A plate 259 at the rear of pawl 243 and in the same vertical plane as a bent shoulder 263 of the pawl, is carried by a pair of arms 260 and 261 hung 75 from pins 262 on the frame of the machine. A spring 264 is extended between arm 261 and a pin on the machine frame and this spring, through the plate 259, serves to urge pawl 243 into engagement with one of the 80 notches in plate 245. The arm 260 carries a pin 265 extending through a slot in a link 266 pivoted at its upper end to a short arm 267 fast to shaft 14.

To adjust lever 131 from one position to 85 another necessitates forcing the pawl or thumb grip 243 toward the lever and thus disengaging its shoulder 242 from one of the notches in plate 245. The rocking movement of pawl 243 forces plate 259 rearward 90 and holds the plate in such position while the lever 131 is being adjusted and shoulder 263 of pawl 243 rides on the outer edge of plate 259. When the lever 131 comes to rest and pressure on pawl 243 is discontinued, 95 spring 264, through arm 261, urges plate 259 forward, thus causing the pawl to re-engage one of the notches 244.

The rearward movement of plate 259 in causing arm 260 to rock rearward, raises 100 link 266 upward and thereby, through the arm 267, rocks shaft 14 in the proper direction for causing rod 254 (Fig. 2) to be positioned to prevent the depression of value 105 keys by preventing movement of their detents 256, but when the pawl 243 is permitted to resume its normal position the rod 254 returns to its normal position through a reverse operation of the above described connecting mechanism under the action of 110 spring 264. Thus the thumb grip or pawl 243 and its connections to rod 254 are operative to prevent a depression of value 115 keys only when the pawl is disengaged from one of the notches in plate 245.

It was previously described how the depression of a department key 21 (Fig. 5) results in a clockwise rocking of arm 16 and frame 29 (Fig. 2). This rocking movement is employed to lock lever 131 against manipulation so that it cannot be adjusted during an operation of the machine. For this purpose frame 29 is connected by a sleeve 252 surrounding shaft 14 to an arm 268 fast to the sleeve. This arm has a bent 120 extension 269 which, when the sleeve rotates slightly on the depression of a department key, moves above a shoulder 270 on plate 259. It is therefore impossible to force the plate inwardly and upwardly around the 125 130

- 5 pivot pins 262 by means of the thumb grip 243 during an operation of the machine. Conversely, when lever 131 is in some intermediate position or in movement with the 10 pawl 243 disengaged from plate 245, it is impossible to release the machine by the depression of a department key, as at such time shoulder 270 of plate 259 is in the path of lug 269 on arm 268.
- 10 15 The lever 131 is primarily intended to adjust mechanism for controlling total and subtotal printing operations, and for this purpose extends downward and rearward from its pivot 61 and at its rear end carries a rod 129 by which certain pitmen may be selected to control the engagement of totalizers with actuators by which the totalizers may be reset. The construction and operation of these pitmen will appear farther on.
- 20 25 *Differential mechanism.*—The differential mechanism consists mainly in a plurality of segment gears 39 (Fig. 2) one of which is provided for each denomination included in the totalizing capacity of the machine. There would therefore be one segment for each amount bank of keys and such extra ones as are required to make up the full number of denominations represented in the totalizers. The segments 39 in design and 30 operation are as shown and described in the before mentioned Kettering and Chryst applications. Each segment (Figs. 2 and 3) is pivoted to a pin 41 extending from the side of its corresponding key frame 24 and also on each pin 41 is pivoted a pair of segment racks 107 and 108 which are connected to segments 39 by pins 1511 on the segments 39 passing through short slots 151 in the segment racks 107 and 108. These slot and 35 pin connections permit the segment racks to move one unit relatively of the segments 39 for the purpose of accomplishing carrying operations. Each segment is provided with a shoulder 38 for coöperating with the shanks of keys and thereby regulating the movement of the segments. Each segment is also connected by a spring 40 to a rod 42 fixed at the rear of the machine. A rod 42 passing below the segments normally retains them in the position in which they are shown in the drawings. This rod is carried by a pair of arms 43 (Fig. 5) pivoted on studs 44 and having rollers 45 at their rear ends extending through jaws 46 in bell 50 55 crank levers 47 journaled on shaft 8 and in turn having rollers 48 extending into cam grooves 49 in disks 50 fast to drive shaft 1. On the depression of value keys the zero stops 37 are moved out of the paths of shoulders 38, as previously described, permitting the segments 39 to rock in a counter-clockwise direction under the action of their springs 40, but the velocity of the segments is regulated by rod 42 which is driven 60 65 downwardly by the action of cams 50 operating on roller 48 first to rock bell crank levers 47 in a clockwise direction and thereby cause the frames 43 to rock in a counter-clockwise direction. The segments therefore follow rod 42 until their shoulders 38 engage the shanks of depressed keys. In this manner the rack segments 107 and 108 are differentially set and on the return movement of segments 39 are caused to actuate their respective totalizing devices. The return movement of segments 39 is caused by the return of rod 42 to normal position as driven by its connections to cams 50.
- 70 75 To insure accurate alinement of the segments 39 when in their differentially adjusted positions, so that totalizers may be properly engaged with racks 107 and 108, pawls 66 are provided, pivoted on arms 67 secured to a shaft 68. Fast to shaft 68 is a downwardly extending arm 70 (Fig. 5) provided with a pin 73 passing through a slot 75 in the pitman 72 pivoted at its rear end by a pin 74 to bell crank lever 47. A spring 69 is extended between pin 73 and a pin 71 on pitman 72. In operation the spring 69 normally holds shaft 68 in such angular position that the pawls 66 do not engage alining teeth 391 (Fig. 3) on segments 39, but when the segments are at rest in their moved positions the clockwise rocking of bell crank lever 47 forces pitman 72 forwardly and thereby releases tension on spring 69 and the continued movement of the pitman 72 causes the shaft 68 and its arm 67 to rock in a clockwise direction and thereby engage pawl 66 with the alining teeth 391. The slot 75 in pitman 72 prevents the pitman from positively engaging pin 73 on arm 70 until rod 42 nearly reaches its lowermost position and for this reason the pawls serve to check vibration of the segments previous to their positively alining and locking the same through the rear edge of slot 75 engaging pin 73. The arms 67 supporting pawls 66 are provided with pins 661 to prevent the pawls from rocking counter-clockwise. This is to safeguard against slow action of the segment driving springs 40. Springs 40 in becoming aged and sluggish in their action might fail to drive the segments 39 the required distance before pawls 66 are engaged therewith; consequently if the pawls would not permit the required stroke of segments 39, an incorrect entry would result. By providing these one-way pawls the segments may continue to lower after the pawls have been rocked in engagement therewith, but the pawls still serve to prevent rebound of the segments when their shoulders 38 strike depressed keys.
- 80 85 90 95 100 105 110 115 120 125 130 The particular alining devices provided in this invention are thought to be of considerable importance to types of account-

ing machines wherein the differential actuators are spring driven, as no dash pots or other protecting devices are required, on their account, to limit the speed of operation of the driving mechanism. It will be understood that springs, in accounting machines, as a rule, require that considerable time be provided for their operation, and accordingly dash pots or spring controlling devices are provided to prevent excessive speed of the driving mechanism. By this simple change in alining devices which the present invention provides, the necessity for considerable controlling mechanism for the driving mechanism is eliminated. The segments 39 also have connections for determining the setting of the type carriers in the printing mechanism. (Figs. 2 and 5). These connections consist of a plurality of beams 51 pivoted to the segments by pins 52 at one end and at their opposite ends pivoted to links 54 by pins 53. The links 54 connect the beams with arms 55 fast to shafts 56 leading to the printing mechanism. At the center of beams 51 are rollers 87 for coöperating with V shaped cam arms 85 fast to a shaft 86. Shaft 86 also carries fast an arm 88 connected by a link 89 to an arm 90 loosely journaled on shaft 8, and which has a roller 91 extending into a cam groove 92 in disk 50. Through this connection cams 85 are rocked rearwardly, when segments 39 are at rest, into engagement with rollers 87 of such of the beams 51 as have been displaced from normal position and as segments 39 are locked in adjusted positions, as above described, beams 51 are compelled to rock around their pivots 52 by the action of cams 85. This movement in direction depends upon the extent of forward rocking of segments 39 and the adjustment of beams 51 on the preceding operation of the machine, and likewise the extent of their movement corresponds to the difference between these two movements. Thus the rear or lower ends of beams 51 are finally adjusted to positions which correspond with the adjustment of their segments 39 and accordingly, through their connections to the type carriers, the latter are properly adjusted backward or forward from their preceding settings as required.

Totalizers.—The totalizing devices 105 and 106 (Fig. 3) are adapted to be meshed with and operated by the segment racks 107 and 108.

The main totalizer 105 is described in the before mentioned patent application of Kettering and Chryst, Serial No. 451,446, and for the purposes of the present application it is thought necessary only to point out that it comprises a plurality of pinions which are journaled on a rod carried by a frame 109 which is secured to a rod 111.

This rod is journaled in the side frames of the machine and carries an arm 113 (Fig. 9) which has a roller 115 extending through an eccentric slot 117 in the lever 119 pivoted to the frame of the machine by a pin 121. The lever 119 carries a rod or stud 123 extending between shoulders 128 of a pitman 125 which is forked at its lower end over shaft 1 and is also provided with a slot 132 through which passes the rod 129 on total lever 130. The pitman is further provided with a slot 136 through which passes a pin 137 extending from a lever 140 journaled on shaft 8. The lever 140 has a roller 143 extending into groove 145 in cam disk 133. The cam groove in cam disk 133 is such that on rotation of drive shaft 1 lever 140 is rocked at the required time to, through the pitman 125, lever 119, arm 113, and shaft 111, rock the totalizer carrying frame 109 so that the totalizer will be held in mesh with the actuating racks 107 during their return stroke.

The department totalizers 106 are journaled on a rod 158 carried by a frame 110 journaled on shaft 112 but rockable therewith for the purpose of engaging the totalizer with actuating racks. As the frame 110 is connected by ball bearings to a frame 157 pinned to the shaft 112 the ball bearing connection between the frames permits relative horizontal movement for the purpose of differentially positioning frame 110 while compelling both frames to rock in a vertical plane when shaft 112 is rocked. The shaft 112 carries rigidly an arm 114 (Fig. 9) having a roller 116 extending through an eccentric slot 118 in a lever 120 pivoted to a pin 122. The lever 120 carries a short rod 124 which passes between shoulders 128 of the pitman 125 which, as previously stated, is reciprocated by cam 133. The movement of the pitman through the lever 120 and its eccentric slot operating on pin 116, thus rocks arm 114 and the shaft 112 to engage a department totalizer with the actuating racks 108 and to hold the totalizer in engagement with the racks during their return movement. In this manner a selected one of the department totalizers is rotated to receive amounts of transactions.

The supporting frame 110 for the department totalizers 106 is provided with races 152 and 153 for ball bearings 154 resting between them and races 155 and 156 in a frame 157 fast to the totalizer supporting shaft 110. The totalizer pinions 106 are denominationaly grouped on the shaft 158, as described in the Kettering and Chryst application No. 376,830, and are sufficient in number to constitute four totalizing devices corresponding to the four department keys. Thus by shifting frame 112 along frame 157 any one of the totalizers may be brought

into operative relation with racks 108 and at most it is only necessary to shift the frame the distance between four totalizer pinions in order to bring any totalizer into 5 operative position.

It was previously pointed out how the department keys serve differentially to position the totalizer carrying frame 110 along the guide frame 157 by differentially oscillating the segment gear 170 (Fig. 8) which meshes with a rack 172 fast to frame 110. A spring 160 (Fig. 4) normally urges the frame 110 to the right so that a certain set of pinions is normally in position to be actuated by the differential mechanism. This 10 particular totalizer corresponds to the uppermost one of the department keys (Fig. 5) and thus upon its depression a shifting operation does not occur.

It is necessary to align the totalizer carrying frame 110 so that when differentially adjusted along its length a desired totalizer will be accurately positioned into the same 25 vertical plane with the actuators and maintained in this plane during the rocking movement of the totalizer frame. For this purpose the segment gear 170 (Figs. 2 and 8) and the rack 173 are respectively provided with alining teeth 175 and 176 for engagement by an alining device 177 (Figs. 1 30 and 2). This device is fast to a shaft 178 carrying rigidly an arm 179 pivoted at its upper end to a pitman 180 supported by drive shaft 1 and having a roller 181 extending into a cam slot 182 in a cam fast to the drive shaft. At the beginning of rotation of shaft 1 the cam becomes operative to shift the pitman rearwardly and thus engage the alining device 177 with the teeth 35 175 and 176. When the totalizer frame 110 is rocked to engage the totalizer and the segments, the rack 173 is consequently carried downwardly out of mesh with segment 170 but it is retained in the same vertical plane 40 by the alining device 177 which is provided with a curved alining tooth 183 for this purpose. The alining device is not again disengaged from the segment 170 and rack 173 until after the totalizer has been operated 45 and its carrying frames 110 and 157 are rocked to carry the totalizer out of mesh with the segments, which movement again connects rack 173 with segment gear 170.

The keys are released and the alining device 50 177 withdrawn simultaneously after the reengagement of rack 172 with the segment 170. The totalizer frame 110 immediately slides along shaft 112 to its normal position under the action of spring 160, that is, of 55 course, if it has been shifted during the operation of the machine, otherwise when the uppermost one of the department keys is depressed the rocking and alinement of the totalizer is the same but it has no longitudinal 60 movement along shaft 112.

The transfer mechanism for the totalizers is the same in principle as such mechanism as described in the before mentioned patent application of Kettering and Chyrst No. 451,446. To accomplish transfers, racks 107 70 and 108 (Fig. 3) have a movement relative to their respective segments 39 so that they may rotate their respective totalizer pinions one extra unit further than is determined by the differential movement of their companion segments 39. Each totalizer pinion carries a pin 146 by which it may trip a transfer pawl 147 out of the path of a pin 148 on the segment rack 107 or 108 of next higher order, thereby permitting the rack 80 to move the required extra unit under the action of a spring 149 extended between it and an arm 150 of the segment 39.

A single set only of transfer devices is provided for the multiple totalizers and 85 these are loosely pivoted on a shaft 187 mounted in the side frames of the machine, and are in such planes as to be operative only in connection with the particular totalizer in operative relation with the differential mechanism.

The above application No. 451,446 also describes the construction and operation of restoring devices 297 for the transfer mechanism. These devices are permitted to operate at their required time and are then restored by an oscillating rod 298 carried by a pair of arms 299 which in the present case are controlled in their operation by cam 300 fast to shaft 1 and constructed to reciprocate a pitman 301 connected through an intermediate arm 302 to the rod carrying arms 299, and by link 303 to the restoring mechanism for the department totalizers.

The mechanism for restoring the transfer device in the present case has a different time of operation than the mechanism in the application above referred to and also in other accounting machines wherein similar oscillating actuators are employed. Formerly the transfer devices were restored at the beginning of operations of the machine, but in the present case they are restored at the end of operations, consequently in total printing no preliminary operation of the 105 machine is required for the sole purpose of restoring the transfer mechanism. To more fully explain this matter, the operation, in general, in this type of machine, of the differential segments on adding and totalizing operations will be briefly pointed out.

In adding operations the segments move down the required distances and when at rest in their lower positions the totalizing devices are meshed therewith. On the return of the segments the totalizers are rotated thus causing possibly some of the transfer devices to be tripped and permitting the racks carried by the segments to move the extra unit for effecting carrying operations.

When the segments reach their normal position the totalizers are disengaged from the racks and the racks remain in displaced position. Then in most machines of this type 5 on the next operation when the differential segments are moving downwardly the transfer mechanism is restored and consequently when the racks arrive at their home positions they engage the ends of transfer pawls 10 and are thus restored to normal relation with their supporting segments. When totals are taken the totalizers are meshed with their actuating racks before the segments 39 move downwardly, consequently it is necessary 15 to give the machine a preliminary operation to first restore such of the racks as might be displaced on account of previous transferring, in order to print the correct total.

20 In the present case near the end of each operation of the machine after the segments have reached zero position the totalizers are disengaged from their racks and the segments again move forwardly about two tooth spaces and during this time the transfer devices are restored and then the segments are returned to normal position causing the pins 148 on actuating racks to engage the end of the transfer pawls and thereby 25 be resorted to normal position. The rotating drive shaft 1 (Fig. 5) is provided with the cam 50, previously explained, having a cam groove 49 suitable for effecting a desired extra forward and rearward movement 30 of the segments 39 at the ends of operations of the machine. Accordingly with this arrangement a total can be taken without a preliminary operation of the machine as the transfer devices will all be in normal position. 35

40 The present improvement, which eliminates need of preliminary operations in this type of machine before totals are taken, is possible without complications because the machine is driven by rotating drive shafts instead of by an oscillating lever or shaft. To effect the same result in a lever operated machine, would necessitate oscillating the lever slightly after the same had gone 45 through a complete forward and return movement, or providing connections to the operating lever to perform the functions of the cam 50.

45 *Printing mechanism.*—The printing mechanism is constructed to print detail records of transactions in triplicate on inserted slips. The type carriers 63 (Fig. 17) are each fast to one of sleeves 65 to which are also secured pinions 64 meshing with segment gears 62 50 journaled on shaft 61. Also journaled on shaft 61 are a plurality of levers corresponding in number to the segment gears 62. These levers are constructed to be connected with the segment gears by pawls 192 pivoted 55 by pins 193 to the segment gears and having

shoulders 194 for engagement with cut out portions 195 of the levers 60, as shown in Fig. 17^a. The levers 60 at their lower ends are pivoted to links 59 which connect them to arms 58 fast to shafts 56 (Fig. 2). In the 60 description of the differential mechanism it was stated that the shafts 56 are oscillated differentially through connections to the differential segments 39, consequently the differential movement of the shafts is communicated to the type carriers 63 by the arms 58, links 59, levers 60, pawls 192, segment gears 62, pinions 64 and sleeves 65. As the cam members 85 (Fig. 2), which serve to differentially drive the shafts 56, do not operate until after segments 39 are at rest in their differentially moved positions, the type carriers are not rotatable with the segment gears 39 and therefore the particular time in the operation of the machine at 65 which impressions must be taken is not dependent upon the position of segment gears 39, which latter may be restored to normal position while the type carriers remain in their differentially set positions. 70

75 Alining devices for the type carriers are so timed in their operation as to prevent rotation of the type carriers after the cams 85 (Fig. 2) have operated and during the time that segment gears 39 are being restored to normal position. In this manner the differential mechanism is prevented from disturbing the setting of the type carriers when it is restored, and consequently during 80 this time impressions may be taken. The alining devices for the type carriers are indicated by numeral 76 (Fig. 17) and are loosely pivoted on a rod 81. Also pivoted on rod 81 is a frame 82 having a downwardly 85 extending arm 80 and a flange 84 extending over the upper ends of the alining pawls 76. Between the pawls and frame 82 are springs 83. The arm 80 is pivoted to a pitman 79 supported at its rear end by shaft 1 and having a roller 78 extending into a cam groove in a cam disk 77 fast to drive shaft 1. This cam, by reciprocating pitman 79, rocks the alining pawls into or out of engagement with pinions 64 by means of 90 the frame 82 and the springs 83 interposed between the frame and the pawls and the flange 84. The springs 83 permit variation 95 in size and adjustment of pawls 76. 100

105 Date printing type wheels 272 are journaled on shaft 651, as shown in Fig. 19, 110 which is a detail of these type wheels and manually operative levers 273 having gear teeth 274 meshing with pinions 275 fixed to the type carriers 272. The levers 273 are pivoted on fixed rod 276 and project 115 through slots 277 in a suitably marked dial plate 278. By shifting levers 273 the date wheels may be set as desired and as these 120 are the same in size as and are mounted in alinement with the value type carrier 63, 125 130

impressions from wheels 272 will occur at the side of the impressions from wheels 63.

Fig. 20 shows a detail of an operator's number key and machine locking device controlled thereby. The number key bears identifying type 294 which, by insertion of the key, are positioned for impressions. The number key 279 is insertible in a fixed tube 280 and has a notch 281 which, when the key is properly positioned, is entered by a plunger 282 carried by an arm 283 fixed to a stub shaft 284 journaled in one of the side frames of the machine. A forked arm 285 is also secured to shaft 284 and has a point 286 to which is secured a spring 287 extending from the pin to a stub shaft 288 on the machine frame. Pivoted on stub shaft 288 is a bell crank lever 291 having shoulders 290 and 296 for respectively operating with a shoulder 289 and a part 295 of the forked arm 285. Pivoted to the bell crank lever is a link 292 connecting it to an arm 293 fast to shaft 11. It was previously pointed out that shaft 11 is rocked by the depression of a department key for the purpose of releasing the machine by rocking pawl 10 (Fig. 1) out of engagement with the disk 9. Consequently when a key 279 is inserted in tube 280 by engagement with plunger 282 it forces the latter upwardly, thereby, through arm 283, rocking shaft 284 and arm 285 in a counter-clockwise direction. The extension 295 of the arm 285 is therefore positioned in front of shoulder 296 of bell crank lever 291 and consequently a rocking movement of shaft 11 in the direction indicated by the arrow cannot occur. However when the key 279 is properly adjusted plunger 282 becomes seated in notch 281 in the key and the arm 285 is, under the action of spring 287, permitted to assume the position in which it is shown in Fig. 20 and it does not prevent a rocking movement of shaft 11 on the depression of a department key. If the key 279 is not in the tube 290 plunger 282 will rock still farther downwardly under the action of spring 287, permitting arm 285 to be rocked downward so that its shoulder 289 engages shoulder 290 of the bell crank lever 291. Consequently the shaft 11 cannot be rocked and the machine is prevented from being released and operated when one of the identifying keys 279 is not in the tube 280.

55 The impression mechanism is shown in Figs. 14 to 16. The sales slip is inserted in a chute 204 (Fig. 14) previous to rotation of drive shaft 1. At the bottom of chute 204 is a plate 205 secured to a knife 104 carried by arms 206 secured to shaft 61 and to one of which is pivoted, by a pin 207, a pitman 208 supported at its rear end by shaft 1 and having a roller 209 coöoperating with a cam groove 210 in a disk 211 secured to shaft 1.

Pivoted loosely on shaft 216 supported in the frames of the machine are arms 220 supporting at their lower end a platen roller 221. Connecting the arms 220 is a rod 219 passing between flanges 217 on a lever 215 pivoted on the shaft 216 between the arms 220. The lever 215 at its rear end is pivoted to a pitman 214 guided by drive shaft 1 and having a roller 213 coöoperating with a cam groove 212 in a disk 211, this groove being on the opposite side of the disk in which the groove 210 is cut. Set screws 218 are provided in the flanges 217 for regulating the angular relation between arms 220 and lever 215 and thereby the force of impressions.

For the purpose of feeding a sales slip there is also loose on shaft 216 an arm 230 on which is pivoted a stub shaft 229 carrying fast a feed roller 228 and a pinion 227. The latter meshes with a segment gear 226 journaled on shaft 216 and connected at its rear end with a pitman 225 guided by shaft 1 and having a roller 224 to be operated by a cam groove 223 in a disk 222 fast to shaft 1. The feed roller 228 coöperates with a feed roller 234 carried by an arm 232 pivoted on a rod 233 and united with arm 230 by a spring 231. The arm 232 has an upwardly extending shoulder 235 engaging a fixed pin and thereby prevents feed roller 234 from moving toward feed roller 228 and segment gear 226 has a flange 236 extending over the forward edge of arm 230 and thereby normally prevents spring 231 from drawing feed roller 228 into contact with roller 234. In this manner the feed rollers do not normally interfere with an insertion of a sales slip in chute 204.

In operation, a sales slip is inserted in chute 204 (Fig. 14) previous to rotation of drive shaft 1. It drops downwardly so that its rear edge rests on the plate 205. On rotation of drive shaft 1 after the type carriers have been previously set, as previously described, the cam 211 by its platen operating groove 212 draws pitman downwardly and thus through lever 215 operating on rod 219 causes the platen carrying arms 220 to be rocked downwardly, whereby the platen forces the slip into contact with the type carriers effecting the first impression. The platen is returned to normal position and then the groove 210 in cam 211 draws pitman 208 rearwardly a slight distance thus withdrawing plate 205 from chute 204, but this movement of the pitman 208 is not sufficient to cause the knife 104 to sever the sales slip. On the beginning of rotation of shaft 1 previous to the taking of the first impression, cam groove 223 (Fig. 15) causes pitman 225 to be slightly lowered thus rocking segment gear 226 slightly in a counter-clockwise direction thus permitting spring 231 to draw the arm 230

toward arm 232 bringing the feed rollers 228 and 234 into engagement. Then after the first impression and after plate 205 has been withdrawn from the chute 204 the 5 pitman 225 is drawn downwardly still farther thus, through the segment gear 226, rotating the feed roller 228 to lower the slip a slight extent. After this feed of the slip occurs a second impression is taken by another operation of pitman 214, the cam groove 212 being suitably formed for this purpose as shown in Fig. 16. Then a further feed of the slip in a downward direction takes place by a further downward 10 movement of pitman 225 as controlled by cam grooves 223 (Fig. 15). Then the third impression on the slip is taken by the action of cam groove 212 and simultaneously with this impression the groove 210 (Fig. 14) 15 in cam 211 draws the pitman 208 rearwardly far enough to cause the knife to sever the sales slip, thus the part of the slip which receives the first impression is cut from the remainder of the slip and deposited in a 20 receptacle 100. The further rotation of drive shaft 1 causes the return of the pitman 214 (Fig. 16) and the return of platen 221, also a reverse rotation of the feed rollers 228 and 234 by the restoring of pitman 225 and the segment gear to which it is 25 pivoted. At the same time cam 211 restores pitman 208 to normal position thus returning the knife to its normal position and plate 205 into the chute 204.

30 An ink ribbon 238 passes between the type carriers 63 and the slip supporting chute 204 from one to the other of rollers 239 and 240 and guided by small rollers 241. The ink ribbon may be fed by manually rotating one of the rollers 239 or 240, or if desired, a suitable mechanical feeding device may be provided but has been omitted from the drawings.

35 On total printing operations the printing mechanism operates as above described making triplicate impressions on an inserted slip, but in such operations the type carriers are set, through the differential mechanism, not under the control of the keys, but as controlled by stops on the totalizer pinions which, during a backward rotation of the pinions, serve to stop the same and the differential mechanism when the differential mechanism has moved the required extent.

40 Total printing.—Total printing operations are controlled by lever 131 (Fig. 9). The construction of this lever and certain interlocking devices coöperating therewith 45 has been described. The manner in which it controls total printing operations will now be pointed out. At the side of the totalizer connecting pitman 125 are two pitmen 126 and 127 (Figs. 10 and 11). Each 50 of these pitmen is provided with a slot 132

through which extends stud 129 on the extension 130 of the total lever and whereas the pitman 125 has shoulders 128 for co-operating with studs 123 124, the pitman 126 (Fig. 12) has shoulders 246 and 2247 70 for co-operating with the studs 123 and 124 but which are normally disengaged therefrom, and pitman 127 (Fig. 13) has a pair of notches 2270 and 2271 for coöperating with the studs 123 and 124. Pitman 125 75 is driven by a cam 133, as previously described, and pitman 126 is driven by a cam 134 for which purpose the latter is furnished with a cam groove 145 into which extends a roller 143 on an arm 141 pivoted on shaft 8 and having a pin 138 extending through a slot 136 in the pitman. Pitman 127 is driven by a cam 135, the groove 145 of which coöperates with a stud 143 on an arm 142 also pivoted on the shaft 8 and 80 having a pin 139 extending through a slot 136 in the pitman. As all of cams 133, 134 and 135 are fast to drive shaft 1, they will be operated on each operation of the machine but their effectiveness is determined 85 by lever 131. This lever when in its central position, as shown in the drawings, through the rod 129, holds the pitmen in the angular position shown in the drawings and pitman 125 is the only operative one, 90 the cam for driving said pitman being suitably formed to effect engagement of the totalizers with their actuating racks for purposes of addition, as previously described.

To effect total or subtotal printing, lever 100 131 (Fig. 9) is adjusted away from its normal or central position. For instance, if it is desired to print a total from the main totalizer, lever 131 is adjusted one step downwardly so that shoulder 242 of the spring 105 pressed thumb grip 243 enters the second notch from the bottom of plate 245. Such adjustment of lever 131 through the stud or rod 129 carried by its rearward extension 130, serves to rock pitman 125 upwardly 110 around shaft 1 to an ineffective position with its shoulders 128 away from rods 123 and 124 on the totalizer controlling arms 119 and 120. The same movement of lever 131 serves to rock pitman 126 (Fig. 12) into co-operative relation with rod 123 on the main totalizer, controlling arm 119, the pitman 126 having the shoulders 246 suitably positioned for this purpose. Also such movement of lever 131 is not sufficient to make 115 pitman 127 (Fig. 13), which controls subtotalizing operations, effective. Consequently by such an adjustment of lever 131 only one of the pitmen will be operative and that the pitman 126, which will be in 120 operative relation with the rocking mechanism of the main totalizer only. Its driving cam is suitably formed to hold the main totalizer in engagement with the totalizer actuating racks 107 (Fig. 2) during the for- 125 130

ward stroke of the actuating racks. The extent of movement of the segment racks is, on total printing operations, controlled in the well known manner by transfer devices which on such operations serve to stop the totalizer pinions, when being backwardly rotated, at zero positions and thus determine the extent of differential movement of the actuating racks. The type carriers are set according to the movement of the differential mechanism on total printing operations in the same manner in which they are set when items are entered in the machine. Also the impressions of totals are taken in the same manner in triplicate on an inserted slip, the stub of which is deposited in a receptacle within the machine. If the lever 131 is positioned one step above its central position, all of the pitmen are made inoperative with respect to rod 123 and the pitman 126 has its shoulder 2247 brought into operative relation with rod 124. In this case when the machine is operated a total will be printed from a selected one of the department totalizers, the department keys determining this selection in the usual manner. In subtotal printing the operation is much the same except that pitman 127 is made effective while the pitmen 125 and 126 are made ineffective and this pitman serves to control the rocking mechanism for the totalizers to hold them in mesh during the entire forward and return movements of the actuating segments so that the reverse rotation of the totalizer pinions on the forward movement of the segments may be employed to set the type carriers and the return movement of the segments to restore the total amounts to the totalizer. If lever 131 is adjusted to its lowest position it will engage notch 2270 of pitman 127 (Fig. 13) with the rod 123 and because of the formation of groove 145 in cam 135, the main totalizer will be held in engagement with the actuating racks during their operation. If the lever is adjusted to its highest position, pitman 127 will be similarly connected with the controlling arm 120 for the department totalizers. In that case a subtotal will be printed of the amount accumulated by the department totalizer.

The total lever 131 has connections shown in Fig. 9 for setting a type carrier to print characters indicating that an amount is a total or subtotal. This type carrier is set by a segment gear 60, being the second from the right (Fig. 18), through a link 59 connecting the same to an arm 58 secured to the lowest one of the shafts 56 (Fig. 9). This shaft carries rigidly an arm 551 pivoted at its forward end to a link 550 connecting it to the total lever 131. It will therefore be seen that the differential movement of the total lever, is communicated through the link 550 and arm 551 to the lowest shaft 56

and from it to the corresponding type carrier.

Frequently in the printing mechanisms of accounting machines means are included for preventing the printing of ciphers to the left of the highest denomination represented in any one printed number. Such mechanism is provided in the present case specially adapted to eliminate ciphers in the higher type carriers when these carriers are set directly from one position to another without first returning to a normal zero position. It is in this respect that it mainly differs from prior devices of this nature. Each type carrier is provided with the usual nine digits and with the exception of the type carrier of highest order, has a cipher. Each type carrier except the lowest two is provided with a blank space on its periphery in order that it may be adjusted to present such blank space to the printing line, for the purpose of preventing impressions from such type carrier when amounts are recorded not involving the higher order type carriers.

Cams 85 (Fig. 2) are constructed ordinarily to position the type carriers at zero when not controlled by value keys or totalizers, but the cipher eliminating mechanism shown in Fig. 17 is provided to rotate the type carriers of higher order beyond the zero position to present said blank spaces to the printing line when required. The condition of the mechanism as shown in Fig. 17 is as it would appear with the desired ciphers eliminated after an operation. The following description points out how during an operation the eliminated ciphers are first restored and then how such as are not required in a new operation are moved out of printing position. The cipher eliminating mechanism consists of a pitman 188 operated by a groove 189 in cam 77 acting on a roller 190 pivoted on the pitman. The latter is located at the side of a segment 62 for the tens of thousands denomination and has means for rocking the said segment one unit of its movement relatively of its driving lever 60, thus causing the segment to rotate its respective type carrier from presenting a blank to the printing line in case this segment stood with a blank space in printing position to present a cipher. The upper end of pitman 188 is provided with a notch for engaging a pin 191 extending from the side of the pawl 192 pivoted on the tens of thousands segment, consequently on the downward movement of the pitman the shoulder 194 of the pawl rides downwardly over the inclined edge 200 of lever 60, the shoulder 194 finally entering notch 195. Its engagement with incline 200 results in the pawl being cammed forwardly and consequently rotating segment gear 62 one unit of its movement in a counter-clockwise direction. This movement of the segment 130

gear results in a corresponding rotation of the type carrier driven thereby causing the same to move from a blank position to present a cipher at the printing line. The pawl 192 pivoted to the tens of thousands segment is provided with a pair of flanges 196 extending over a pin 197 carried by a pawl 192 pivoted to the segment 62 of next lower order, which later pawl also has flanges 196 extending over a pin 197 of the next lower segment and so on down to the cents and tens of cents segments, which are not provided with pawls 192 but are made in one piece with driving arms 60, as it is not desired to eliminate ciphers in the type carriers driven by these segments. The flanges 196 and pins 197 thus serve to communicate the movement of pitman 188 to lower order type carriers. This movement can only take place in segments 62 which have been moved to eliminate ciphers on the preceding operation of the machine, as such of the segments as were moved away from the position in which they cause blanks to be positioned at the printing line of the preceding operation of the machine, would be disconnected from pitman 188 as the pins 197 carried by their respective pawls 192 would not be in coöperative relation with flanges 196 of the pawls of higher order. While the pitman is in its lower position the type carriers are differentially set by the differential operation of segments 62 through driving levers 60 and connections to the differential mechanism previously described. After the type carriers are set the pitman 188 is returned to the position shown in Fig. 17 thus, through the pawl 192, rocking its segment 62 backward an extra unit to eliminate the cipher. As the upward movement of the pitman causes tail 198 of pawl 192 to engage shoulder 199 of lever 60 and consequently cam the segment 62 the desired unit, this movement is communicated by pawl 192 of the tens of thousands bank to the lower order pawls through the flanges 196 and pins 197 down to the particular segment which has been set away from zero position on the setting of the type carriers.

On total printing operations the cipher eliminating mechanism may not be required at all as the tens of thousands type carrier may be employed in printing the total and consequently the pin on pawl 192 carried by the segment 62 for such type carrier may be moved out of engagement with the notch in pitman 188.

In order that the lever 60 operating the tens of thousands segment 62 may be prevented from movement while pitman 188 is causing the pawl 192 to engage the lever 60 and thereby receive movement from the same, the lever 60 is provided with a small spring actuated pawl 201 for hooking over a fixed rod 202 when the arm 60 is in its normal position. The rod also passes in front of the forward edge of arm 60 and thus in connection with the pawl normally prevents the arm from rocking in either direction when the pitman is being lowered and lifted. As stated, the differential mechanism operates when pitman 188 is in its lower position, and in order that pawl 201 may not interfere with the operation of the differential mechanism for the tens of thousands denomination on total printing operations, when the printing segment for this denomination may be differentially set, pitman 188 carries a pin 202 for engaging pawl 201 to rock it away from the rod 202 and thereby permit the differential setting of this segment when pitman 188 is in lower position.

Slip receptacle.—Below the printing mechanism as shown in Fig. 14 is a slip receptacle 100 having a plurality of compartments 103 corresponding to each department key or department totalizer. The department keys control means for differentially adjusting the receptacle 100 along guide ways 102. A carriage 99 which supports the receptacle is provided with rollers fitting in the guides 102 and also has upwardly extending arms 98 provided with rollers extending through the forked ends of arms 96 fast to shaft 95. Shaft 95, as shown in Fig. 5, also has rigidly secured to it an arm 93 which is connected by a pin 94 to link 54 which in turn is pivoted by a pin 53 to beam 51 controlled in its movement by the department keys 21 and cam member 85, as previously described. This beam 51 for the bank of department keys thus serves to differentially set the slip receptacle forward or backward in addition to its work of setting the department type carrier. In this manner the desired one of the compartments 103 is brought below the slip cutting mechanism, resulting in the stubs being classified according to the departments to which their respective transactions relate.

A cash drawer 325 (Fig. 2) is provided which as usual is spring driven to its open position and is constructed to be released at each operation of the machine and also may be released through means of a manually depressible key at any time. At the rear of the cash drawer (Fig. 2) is a bracket 326 over which hooks a drawer latch 327 normally held in engagement with the bracket by a spring 328 extended between the latch and a link 329 connecting a pitman 330 with a lever 331 pivoted to the casing of the machine by a pin 332. The lever 331 has a pin 333 passing through a slot in latch 327, and when pitman 330 is engaged by a pin 334 on cam 26 lever 331 is rocked in a clockwise direction and through the pin 333 raises latch 327 and thus releases the cash drawer. The pitman 330 may be lifted and release the

cash drawer independently of the operating mechanism of the machine by a depressible key 335. The shank of this key bears on a lever 336, pivoted to the machine frame by a pin 337, and at its rear end passing beneath a pin 338 on link 329. Consequently when the key 335 is depressed, pitman 330 is lifted and through it lever 331 is rocked and the cash drawer thereby released. At its lower end lever 331 is provided with a pawl 340 for operating a hammer 341 for a bell 342. Consequently, whenever the cash drawer is operated, whether by an operation of the machine or by depression of key 335, hammer 341 is forced forwardly and then permitted to strike the bell under spring action.

In several views, Figs. 3, 5, 9, and 12 to 17, are shown cam disks in which the grooves open out radially to the peripheries of the disks. It readily will be seen that by this construction the assembling of pitmen into the machine or their removal may take place without a sidewise movement of the cams or their supporting shafts, which in accounting machines is frequently difficult to accomplish because of close mechanism, and requires a certain order of assembling or further dismantling as the particular design of the machine compels.

Operation.—To operate the machine for the purpose of entering an item, it is necessary that lever 131 be in its central position and that an operator's key 279 (Fig. 20) be properly positioned. When lever 131 is in its normal central position, the mechanism controlled thereby is in proper position for controlling the machine, to cause addition in whatever department is selected and also in the main totalizer. The key 279 renders the machine locking mechanism, shown in Fig. 20, inoperative. The only manipulation of the machine required on entering an item, if the lever 131 is in normal position and a key 279 properly adjusted, is to depress value keys according to the amount of the entry, and the desired department key. Depression of the department key through the connections to the department totalizer carrying frame 110 (Figs. 2, 4, 5 and 8), serves to position the corresponding totalizer by longitudinal shifting of the totalizer carrying frame. The depression of the department key also releases the machine by permitting the rocking movement of pawl 16 (Fig. 5) and thus through its connections to pawl 10 (Fig. 1) permitting the release of the motor clutch 9 and the closing of the motor circuit. The drive shaft then makes one rotation before the clutch is disengaged and the motor circuit opened.

Rod 42 (Figs. 2 and 5) first is carried downwardly by operation of bell crank lever 47 and is followed by segments 39 under the action of their springs 40. When the seg-

ments are at rest and alined in their differentially set positions as controlled by the depressed value keys, the main totalizer and the selected department totalizer are connected respectively with racks 107 and 108 70 carried by segment gears 39. The differential movement of the segment gears serves differentially to position beams 51 (Fig. 2), and while the segments are at rest cams 85 are drawn rearwardly by their connections 75 to a cam on the main drive shaft, as shown in Fig. 5. Such rearward movement of the cams causes them to engage rollers 87 on beams 51 and through the link connections of the beams to the type carriers, positions 80 the type carriers according to the differential movement of segments 39 and differentially adjusts the stub receptacle 99 (Fig. 14). Three impressions are then taken one after another, and each includes the amount 85 of the item, a character indicating the department totalizer which is operated, this type carrier being set similarly to the amount type carrier, an operator's identifying character, as determined by the operator's key as shown in Fig. 20, and the date as determined by the setting levers 273 (Fig. 19). The slip is cut and the stub deposited in one of the compartments of receptacle 99. 95

At the time of the impression the totalizers are connected with the actuating racks and then the rod 42 (Fig. 2) is returned to its upper position, thus driving the segments 39 to home positions and thereby adding the amount of the transaction to the main totalizer and the selected department totalizer. When these segments have reached their home positions the totalizers are rocked out of mesh by the restoring movement of pitman 125 (Fig. 9) which serves to control 105 the connection and disconnection of the totalizers and the segments.

To print the total of either a department totalizer or the main totalizer, the lever 131 is either adjusted one step upwardly to the 110 total printing position for the department totalizers or one step downwardly to the total printing position for the main totalizer. Its positioning then serves to connect the pitman 126 (Fig. 12) with the desired totalizer controlling arm 119 or 120. Also, a manipulation of lever 131 prevents depression of any of the value keys by causing rod 254 (Fig. 2) to move to the front of the shoulders 255 of the detents of the value 115 keys. This movement of rod 254 rocks zero plungers 37 out of the path of movement of shoulders 38 on the differential segments 39. Then, on the depression of a department key, the machine is released and if a department 120 totalizer is being reset, it is positioned to be operated by racks 108 (Fig. 3). The operation of drive shaft 1, through the pitman 126, immediately causes the selected 125 totalizer to be connected with its actuating 130

racks, and then rod 42 (Fig. 2) is rocked downwardly and the totalizer reversely rotated to zero position, when an impression of the total is taken. The return movement of rod 42 serves to return the actuators 39 to zero position, while the totalizer is held out of mesh by its pitman 126, thus the totalizer is permitted to remain in its reset position.

If the lever 131 is adjusted to its lowest position, pitman 127 (Fig. 13) becomes operative with respect to the main totalizer controlling arm 119, then on the operation of the machine the pitman serves to hold the main totalizer in mesh both during the forward and return movement of the actuators 39. The subtotal is printed when the actuators 39 are alined in their moved positions. The return movement of the actuators serves to restore the previous amount to the totalizer. If lever 131 is adjusted to its highest position, pitman 127 becomes effective to rock the department totalizer controlling arm 120 and this serves to hold the selected department totalizer in mesh both during the forward and return movements of actuators 39. Accordingly after the impression is taken of a subtotal from one of the department totalizers, the amount is restored to the respective department totalizer as pitman 127 is not returned to its normal position until after the actuators 39 have been returned to normal position.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the claims which follow.

What is claimed is:

1. In a machine of the class described, the combination with printing mechanism, of means for differentially setting the same and taking impressions therefrom, and a differentially adjustable slip receptacle operative with the printing mechanism to receive separately printed slips in different positions.
2. In a machine of the class described, the combination with printing mechanism, of means for taking impressions therefrom, a slip receptacle, differential mechanism for adjusting the printing mechanism and having connections to differentially adjust the slip receptacle, and manipulative devices adapted to control the differential mechanism.
3. In a machine of the class described, the combination with differential mechanism, of a plurality of totalizers adapted to be selectively actuated thereby, keys for selectively positioning the totalizers in operative relationship with the differential mechanism, a plurality of slip receptacles, and

connections whereby the keys for positioning the totalizers correspondingly selectively control the positioning of the slip receptacles.

4. In a machine of the class described, the combination with a slip receptacle having a plurality of compartments, of operating means for moving the slip receptacle, a set of keys, and connections whereby the keys control the movement of the slip receptacle by the operating means and in a manner such that the slip receptacle always is moved from one position directly to another without first returning to some constant position.

5. In a machine of the class described, the combination with totalizer actuating mechanism, of a frame carrying a plurality of totalizers which is differentially adjustable transversely of the actuators and rockable in the plane of the actuators for the purpose of meshing a desired totalizer therewith, and a curved alining member adapted to be engaged with co-acting alining members on the frame and remain in engagement therewith during rocking movement of the frame.

6. In a machine of the class described, the combination with differential mechanism, of a plurality of totalizers, means for connecting a totalizer with the differential mechanism, and an adjustable device having connections to select for operation one of said totalizing devices and for determining the time of connection of said selected device for effecting different accounting operations therein.

7. In a machine of the class described, the combination with a plurality of type carriers each having a typeless space, means for differentially setting the type carriers from one setting directly to another, and means for rotating desired ones of the type carriers to present typeless spaces to the printing line.

8. In a machine of the class described, the combination with a plurality of type carriers, of means for differentially setting the type carriers from one position directly to any other desired position, and a cipher eliminating mechanism for the type carriers operative after said differential means.

9. In a machine of the class described, the combination with a plurality of type carriers, elements for differentially positioning the type carriers, driving devices for said elements, means for connecting and disconnecting said elements with the driving devices operative at such time to rotate said elements.

10. In a machine of the class described, the combination with a plurality of type carriers having zero characters and blank spaces, means for moving the type carriers presenting a blank space to the printing

line, so as to position a cipher character thereat, means for adjusting the type carriers after the operation of the last mentioned means, and means for thereafter 5 eliminating the ciphers of the type carriers above the highest one adjusted to print a character other than zero.

11. In a machine of the class described, the combination with a plurality of type 10 carriers having a cipher character and a typeless space, means for variously positioning the type carriers including operatively connectible and disconnectible elements, and means for connecting said elements for the 15 type carriers presenting typeless spaces at the printing line and simultaneously moving said carriers to present cipher characters thereat before the operation of the first named means, and after the operation of 20 said means to disconnect the elements of the first mentioned means corresponding to the type carriers above those adjusted to print characters other than zero and simultaneously move the corresponding type carriers 25 to position typeless spaces at the printing line.

12. In a machine of the class described, the combination with a totalizer, of actuators therefor, differentially movable members 30 carrying said actuators, the latter having movement independent of the carrying members for the purpose of effecting transfers, manipulative devices controlling the differential movement of the carrying members, and mechanism for restoring the carrying members to normal position, the 35 said mechanism permitting movement of the carrying members, during the operation of the machine in which they are restored, in 40 the same direction they are moved under the control of the manipulative devices for the purpose of resetting the actuators that have moved independently of the carrying members in effecting transfers.

13. In a machine of the class described, the combination with a totalizer, of differentially movable actuators therefor, manipulative devices controlling the movement of 45 said actuators, mechanism for restoring the actuators to normal position, and means for imparting an additional movement to the actuators for the purpose of effecting transfers, the said restoring mechanism permitting movement of the actuators, during the 50 operation of the machine in which they are restored, in the same direction they are moved under the control of the manipulative devices for the purpose of resetting the actuators that have been moved an additional step in effecting transfers.

14. In a machine of the class described, the combination with an accounting device, 55 of a spring controlled differentially movable member for actuating the accounting device, an alining device for said member con-

structed to engage said member and prevent its movement against the action of its spring but permit the movement of said member by its spring, and means for differentially limiting movement of said member 70 under the action of its spring.

15. In a machine of the class described, the combination with a differentially movable member, a spring for actuating said member, keys for determining the movement of the member, and an alining device 75 constructed to permit movement of said member by its spring but prevent rebound thereof.

16. In a machine of the class described, 80 the combination with a differentially movable member, of actuating means therefor, means for determining the movement of said member, and an alining device so constructed that when in engagement with the 85 movable member permits the movement of the latter by its actuating means but prevents rebound thereof.

17. In a machine of the class described, 90 the combination with a totalizer, of differentially movable actuators therefor, springs for moving said actuators, keys limiting the movement of said actuators by the springs, mechanism restoring the actuators to normal position and thereby operating the totalizer, and means imparting an additional 95 movement to the actuators for the purpose of effecting transfers, the said restoring mechanism permitting movement of the actuators by their springs during the operation 100 of the machine in which they are restored whereby the actuators that have been moved an additional step in effecting transfers are reset.

18. In a machine of the class described, 105 the combination with a totalizer, of differentially movable actuators therefor, springs for moving said actuators, keys limiting the movement of said actuators by their springs, mechanism restoring the actuators to normal 110 position and thereby operating the totalizer, stops for arresting the actuators in normal position, means controlled by the totalizer for displacing the stops when transfers are to be effected, means for moving the actuators an additional step to effect transfers, and means for so operating the restoring 115 mechanism during a single operation of the machine that the actuators after being restored are permitted to be moved by their 120 springs whereby those of the actuators that have been moved an additional step in effecting transfers are reset.

19. In a machine of the class described, 125 the combination with a printing mechanism, of means for differentially setting the same and taking impressions therefrom upon record material, and a series of receptacles for the record material into any one of which the record material may be deposited, the 130

desired receptacle being selected by said differential means.

20. In a machine of the class described, the combination with a printing mechanism, of means for differentially setting the same and taking impressions therefrom upon record material, a series of receptacles for the record material, and common manipulative devices for determining the receptacle into which the record material is to be deposited and controlling the differential means.

21. In a machine of the class described, the combination with a set of type carriers adapted to print various classes of transactions, of means for taking a plurality of impressions therefrom upon a sales slip and severing a portion of said slip, a series of receptacles, and means for determining the receptacle into which the severed portion of the slip is to be deposited, and determining the class of transaction to be printed by the type carriers.

22. In a machine of the class described, the combination with a type carrier, of an element for differentially positioning said type carrier, a driving device for said element normally disconnected therefrom, and means for connecting the element with the driving device by which connection the type carrier is advanced one step for the purpose described.

23. In a machine of the class described, the combination with a type carrier, of an element for differentially positioning said type carrier, a driving device for said element normally disconnected therefrom, means for connecting the element with the driving device by which connection the type carrier is advanced one step, and means for thereafter operating the driving device whereby the type carrier is differentially positioned.

24. In a machine of the class described, the combination with a printing mechanism, of means for differentially setting the same and taking impressions upon record material, and a series of receptacles for the record material adjustable by the differential means to bring any desired one of the same into coöperative relation with printing mechanism.

25. In a machine of the class described, the combination with a printing mechanism, of means for differentially setting the same and taking impressions upon record material and a series of receptacles for the record material adjustable collectively by the differential means to bring any desired one of the same into coöperative relation with printing mechanism.

26. In a machine of the class described, the combination with a printing mechanism, of means for differentially setting the same and taking impressions therefrom upon record material, a series of receptacles for

the record material adjustable to bring any desired one of the same into coöperative relation with the printing mechanism, and common manipulative means for determining which of said receptacles will be so adjusted and for controlling the differential means.

27. In a machine of the class described the combination with a printing mechanism for printing various classes of transactions, of means for differentially setting the same and taking impressions therefrom upon record material, a series of receptacles for the record material adjustable collectively automatically in accordance to the classes of transactions printed by the printing mechanism to bring any desired one of the same into coöperative relation with the printing mechanism, and manipulative means for determining which of said receptacles will be so adjusted.

28. In a machine of the class described the combination with a printing mechanism, of means for differentially setting the same and taking impressions therefrom upon record material, a series of receptacles for the record material adjustable to bring any desired one of the same into coöperative relation with the printing mechanism, means for adjusting said receptacles, and common manipulative means for determining which of said receptacles will be so adjusted and for controlling the differential means.

29. In a machine of the class described the combination with a printing mechanism, of means for differentially setting the same and taking impressions therefrom upon record material, a series of receptacles for the record material adjustable collectively to bring any desired one of the same into coöperative relation with the printing mechanism, means for adjusting said receptacles, and common manipulative means for determining which of said receptacles will be so adjusted and for controlling the differential means.

30. In a machine of the class described, the combination with a set of type carriers adapted to print various classes of transactions, of means for taking impressions therefrom upon a sales slip and severing a portion of said slip and a series of receptacles adjustable automatically in accordance to the classes of transactions printed by the type carriers to bring any desired one of the same into coöperative relation with the severing means to receive the severed portion.

31. In a machine of the class described, the combination with a set of type carriers adapted to print various classes of transactions, of means for taking impressions therefrom upon a sales slip and severing a portion of said slip, a series of receptacles adjustable automatically in accordance to

the classes of transactions printed by the type carriers to bring any desired one of the same into coöperative relation with the severing means to receive the severed portion, and manipulative means for determining which of said receptacles will be so adjusted and determining the class of transactions to be printed.

32. In a machine of the class described, 10 the combination with a set of type carriers adapted to print various classes of transactions, of means for taking impressions therefrom upon a sales slip and severing a portion of said slip, a series of receptacles adjustable automatically in accordance to the classes of transactions printed by the type carriers to bring any desired one of the same into coöperative relation with the severing means to receive the severed portion, means 20 for adjusting said receptacles, and manipulative means for determining which of said receptacles will be so adjusted and determining the class of transactions to be printed.

33. In a machine of the class described 25 the combination with a plurality of totalizers, actuating mechanism for the same, a printing mechanism for printing on record material, a plurality of receptacles adapted to receive the record material when printed 30 and adjustable to establish a coöperative relation between said printing mechanism and any desired one of said receptacles, and manipulative means for determining which of the totalizers will be actuated and which 35 of said receptacles will be adjusted to coöperative relation with the printing mechanism.

34. In a machine of the class described the combination with recording mechanism 40 adapted to make records of different classes on record material and a series of receptacles adjustable in accordance to the classes of transactions printed to bring any desired one of said receptacles into coöperative relation with the recording mechanism to receive the record material when a record is made on the same.

35. In a machine of the class described the combination with recording mechanism 50 adapted to make records of different classes on record material and a series of receptacles adjustable collectively and automatically in accordance to the classes of transactions printed to bring any desired one of said re-

ceptacles into coöperative relation with the 55 recording mechanism to receive the record material when a record is made on the same.

36. In a machine of the class described the combination with a recording mechanism adapted to make records of different 60 classes on record material, a series of receptacles adjustable to bring any desired one of said receptacles into coöperative relation with the recording mechanism to receive the record material when a record is 65 made on the same, and means for determining which of said receptacles will be so adjusted and determining the class of transactions to be recorded.

37. In a machine of the class described 70 the combination with recording mechanism adapted to make records of different classes on record material, a series of receptacles adjustable to bring any desired one of said 75 receptacles into coöperative relation with the recording mechanism to receive the record material when a record is made on the same and manipulative means for determining which of said receptacles will be so adjusted and the class of transactions to be recorded. 80

38. In a machine of the class described the combination with recording mechanism adapted to make records of different classes on record material, a series of receptacles adjustable to bring any desired one of said 85 receptacles into coöperative relation with the recording mechanism to receive the record material when a record is made on the same and means for so adjusting said receptacles and determining the class of 90 transactions to be recorded.

39. In a machine of the class described the combination with recording mechanism adapted to make records of different classes 95 on record material, a series of receptacles adjustable to bring any desired one of said receptacles into coöperative relation with the recording mechanism to receive the record material when a record is made on the same and manipulative means for so adjusting said receptacles and determining the 100 class of transactions to be recorded.

In testimony whereof I affix my signature in the presence of two witnesses.

HAAKON A. MARTIN.
